WIRING DEVICE

Roland R. Keesee, Prattsville, Ark.

Application December 23, 1935, Serial No. 55,823

1 Claim. (Cl. 173—329)

This invention relates generally to devices employed in house wiring, and particularly to a new type of wiring device for replacing the commonly used ceiling rosette.

The principal object of the invention is the provision of a device for facilitating the wiring of buildings for electric service with multi-conductor cables, through the use of which splicing and tapping of the cable in attics and roof spaces may be avoided, such connections as are necessary being made within the wiring device.

Another object is the provision in a ceiling rosette of insulating means for the conductors passing through the ceiling, so that it may be used on ceilings of conducting material; rosettes heretofore used lacking this advantage and being unsuitable for such application.

With these and such other objects in view as may appear from the description, my invention resides in the particular form of construction, and combination of the component parts of the device.

In the drawings:

Fig. 1 is a plan view of the device, as seen from the lower, or flanged end.

Fig. 2 is a plan view of the removable cover for the device, as seen from above.

Fig. 3 is a section of the device, taken along the line III—III of Fig. 1.

Fig. 4 is a section of the device, taken along the line IV—IV of Fig. 1.

Fig. 5 illustrates the device in the service position.

Fig. 6 is an isometric view of a building in the wiring of which the device has been employed.

Referring first particularly to Figs. 1 and 3, the hollow tube 10, of some suitable insulating material, as porcelain, is provided adjacent its lower end with the integral concentric outwardly extending and downwardly depending recessed flange 11. Within the recess of the latter, and laterally spaced from the opening through the tube 10, are mounted a plurality of conductor terminals. In the embodiment illustrated, three such terminals are shown, which include the first terminal member 14, the second terminal member 15, and the third terminal member 18, these members being rigidly secured within the recess by means of the mounting screws 17, 16, and 20, respectively.

To provide ample leakage distance in a small diameter recess, the integral barrier 21 is interposed between the second terminal member 15 and the third terminal member 18.

For clamping a plurality of conductors to the first terminal member 14, the clamping member

25 is arranged to be drawn theretoward by means of the clamping screw 26, and similarly, the clamping member 19 is arranged to be drawn toward the third terminal member 18 by means of the clamping screw 20. For reasons shortly to appear, no clamping member is usually required for cooperating with the second terminal member 15, the terminal screw 27 amply serving this purpose.

In Fig. 1 the device is shown with one conductor of each of the two-conductor supply cables 22 connected through the first terminal member 14, and the other conductor of each of these cables connected through the third terminal members 18 and 19. One conductor of the two-conductor switch cable 24 is connected to the third terminal members 18 and 19, and the other to the second terminal member 15. It will be obvious that the first and second terminal members will be energized at the supply voltage when the conductors of the switch cable 24 are electrically connected, as through a switch.

Figs. 2 and 3 illustrate a closure for the hollow, or recess, containing the conductor terminals, this closure consisting of a disk 29, of some suitable insulating material, as porcelain. The diameter of the disk 29 is preferably substantially the same as that of the flanged portion 11. A concentrically positioned recess is provided at the upper side of the disk 29, in which are secured the diametrically spaced U-shaped load contacts 30 and 31, by means of the respective load contact mounting screws 36 and 35 (Fig. 4). Each of these contacts is provided with a laterally extending base portion, to which are electrically connected the load conductors 32 and 33, by means of the load terminal screws 42 and 43 respectively. A centrally positioned opening 44 provides an exit from the recess for the load conductors 32 and 33.

The closure, or cover, just described is substantially the same as a well known rosette cover, and does not, in itself, constitute the present invention.

For retaining the cover in position, the diametrically spaced resilient load contact clips 13 and 28 are secured between a wall of the recess of the flanged portion 11 and the first and second terminal members 14 and 15 respectively, the arrangement being such that the load contacts 30 and 31 engage the upper surface of the load contact clips 13 and 28 in response to a rotary movement of the cover 29. The position of the elements under the conditions just described is illustrated in Fig. 4.

The device, designated in its entirety by the numeral 31, is shown secured to an electrically conducting ceiling 41 of a building in Fig. 5. The bolts 40, which extend upwardly through the openings 12 (Fig. 1), rigidly secure the device to the ceiling; the load cable 38, which includes the load conductors 32 and 33, extends downwardly to the lamp socket 39. In this illustration, the cables 22 may be either ingoing or outgoing supply cables, and the cable 24 the switch cable for controlling the supply of energy to the lamp socket 39.

It may be noted that all of the conductors enter the recess of the flanged end 11 through the tubular upper portion 10, the latter extending above the upper surface of the ceiling 41, so that a wall of insulating material is interposed between both the conductors and the conducting terminals, and the conducting ceiling.

20 The manner in which a building may be wired without the necessity of splicing or tapping the cabled conductors at any point above the ceiling, all of the necessary connections being made within the wiring devices 37, is illustrated by Fig. 6. 25 The two-conductor cables 22 are normally energized at the supply potential, while the two-conductor control cables 24 connect the switches 45 to the load circuit of the device 31. A convenience outlet or wall receptacle is designated 30 by the numeral 46. The labor saving through the avoidance of splicing and tapping of the con-

ductors in roof spaces or attics will be apparent from this illustration.

While I have here illustrated and described one embodiment of my invention, other embodiments will appear from the one disclosed herein, and it is to be understood that my invention is to be limited only by the appended claim and the prior art.

What I claim is new, and desire to secure by Letters Patent, is:

The combination with a ceiling rosette of an integral upstanding tubular portion having a relatively large bore for the accommodation of a plurality of two conductor cables, said rosette containing a pair of insulated load terminals and an additional terminal insulated from said load terminals, said terminals including means for connecting one conductor of a two conductor supply cable to one load terminal and the other conductor to the additional terminal, means for connecting one conductor of a second two conductor supply cable to said one load terminal and the other conductor to the additional terminal, means for connecting one conductor of a two conductor load control cable to the other of said load terminals and the other conductor of said control cable to said additional terminal, and detachable means for connecting a load circuit to said pair of load terminals, said detachable means providing a closure for said rosette.

ROLAND R. KEESEE.
